UNITED STATES PATENT OFFICE.

HARRY M. HUSK, OF NEWBURYPORT, MASSACHUSETTS.

DESIGN FOR A SLIPPER.

Application filed December 17, 1924. Serial No. 11,722. Term of patent 3½ years.

To all whom it may concern:

Be it known that I, HARRY M. HUSK, a citizen of the United States, and a resident of Newburyport, county of Essex, and State of Massachusetts, have invented a new, original, and ornamental Design for Slippers, of which the following is a specification, reference being made to the accompanying drawing, forming a part thereof.

In the drawing Fig. 1 is a plan view, and Fig. 2 a side elevation of a slipper showing my new design.

I claim:—

The ornamental design for a slipper, as shown.

HARRY M. HUSK,
